CARTON

Lawrence W. Reaume, Monroe, Mich., assignor to
 River Raisin Paper Company, Monroe, Mich., a
 corporation of Michigan

Application October 22, 1936, Serial No. 106,959

5 Claims. (Cl. 229—52)

The invention relates to cartons or cases and particularly those of the type used for transporting beverage bottles.

Cartons of the above type when loaded are relatively heavy and of rather awkward size to carry. Accordingly, it is preferred to provide a hand hole in one or both of the end pieces of the carton in order that the handler can hold one carton in each hand. This practice has been used for many years but it has been found that when the cartons are made of cardboard or the like that the carton as a whole and the end pieces thereof in particular are of insufficient strength to sustain the entire carton when filled. Accordingly, in many of the cardboard beverage cartons now in use, no hand holes are provided and in those in which hand holes are provided, it has been found that the cartons rapidly deteriorate due to their lack of strength.

Accordingly, it is the general object of the present invention to provide an improved end construction for a cardboard carton of the type mentioned which will not materially increase the cost of the carton but will nevertheless impart sufficient strength and rigidity to the end members to enable the end members to sustain the entire weight of a loaded carton without distortion or deterioration.

A further object of the invention is to provide an improved end piece wherein the portion thereof of above the hand hole is reinforced in a novel manner.

Further objects include the provision of an end piece of the character described which is formed of a single sheet of material and which is secured to the remaining portions of the carton in such a manner that the lifting forces are transmitted directly to the two such portions.

In the drawing, wherein like numerals are applied to like parts in the several views,

Figure 1 shows a perspective view of the carton in a partially opened condition;

Fig. 2 is a fragmentary section of one end of the carton taken on the line 2—2 of Fig. 1;

Fig. 3 is a view of the blank from which the main body of the carton is formed, and

Fig. 4 is a view of a blank from which the improved end piece is formed.

As best shown in Figures 1 and 3, the main body of the carton is formed of a single substantially rectangular blank 10 which is divided from end to end by a plurality of parallel crease lines 11 into a top flap 12, a half top member 13, a side member 14, a bottom member 15, a second side member 16, a second half top member 17, and a second

top flap 18. Suitable finger holes 19 and 20 are preferably provided in the half top members 13 and 17. Side member 14 is provided at its ends with a pair of tabs 21. The bottom member 15 is provided with similar tabs 22 and the second side member 16 is provided with corresponding tabs 23, which tabs are utilized to secure the main body portion of the carton to a pair of end members indicated generally at 25. The connection between the tabs 21, 22, and 23 and the end members 25 may be made in any desired manner but is preferably effected by means of suitable staples 26, as best shown in Fig. 1. After the box is assembled, the usual partition members 27 are inserted therein for dividing the box into a plurality of bottle-receiving compartments.

The improved end members 25 are each formed, as best shown in Figure 4, of a single sheet of cardboard or the like comprising equally sized outer and inner sections 28 and 29, respectively, which are separated by parallel crease lines 30. The blank is folded double along the crease lines 30 to provide an end member of double thickness, as best shown in Figure 2. The outer section 28 is provided with a suitable hand hole 31 and the inner section is provided with an opening 32, the upper edge of which extends flush with the upper edge of the hand hole 31 when the blank is folded in the manner shown in Fig. 2. Opening 32 in the inner section, however, is of greater depth and of substantially greater width than the opening 31. Preferably the opening 32 extends beyond the ends of opening 31 by an amount equal to substantially half of the distance between the end of opening 31 and the side edge of the end member 25 for a purpose to be described. When the end member is assembled, the piece 33, which is removed from opening 32 in the inner section, is positioned between the inner and outer sections 29 and 28 immediately above the upper edge of the hand hole 31, substantially filling the space between the inner and outer sections and above the hand hole and extending substantially beyond the ends of the hand hole. Preferably, piece 33 is not separated from the section 29 but is merely bent along the line 34, as indicated in Figures 2 and 4, to provide a stronger edge formation for the upper edge of the hand hole, but it is apparent that piece 33 may be entirely cut away from section 29 if desired. After the piece 33 is positioned between the inner and outer sections of the end member, it is secured in position in any desired manner, such as by staples 35, as indicated in Fig. 1.

It will be noted that the end member 25 is se-

cured to the inner sides of the tabs 21, 22 and 23 of the main body of the carton, with the result that it is particularly adapted to transmit endwise lifting forces to the body of the carton. 5 Moreover, the end member itself is so formed as to provide unusual strength to resist endwise lifting forces. Not only is the end member doubled to generally increase its stiffness, but the upper edge thereof, which is subject to the greatest 10 stress, is folded double once at the ccrease line 30 and again immediately above the hand hole at the point 34, thus providing a triple thickness of material above the hand hole, which area of triple thickness extends substantially beyond the 15 ends of the hand hole, in order to transmit the lifting forces to those portions of the end member beyond the ends of the hand hole.

The box is closed by folding the half top members into closing position and inserting the top flaps 12 and 18 into the box between the end pieces 25. Preferably, the length of the flaps 12 and 18 is such that they fit snugly between the end pieces 25 with sufficient friction to retain the half top members against unintentional opening. 25

It is apparent in view of the above that there is provided in accordance with the present invention an improved cardboard carton particularly adapted to sustain the endwise forces incurred 30 when the carton is lifted by a hand hole in an end member and that the structure provided is relatively simple and inexpensive.

While only one form of the invention has been disclosed, it is apparent that others are available 35 within the spirit of the invention as set forth in the drawing and description and within the scope of the appended claims.

What is claimed is:

1. An end construction for a carton having a 40 bottom and side walls, comprising a pair of cardboard end pieces positioned face-to-face in contact with each other and secured at three sides to the bottom and sides of the carton, one of said end pieces having a hand hole spaced from the 45 top edge thereof, the other end piece having an opening in alignment with said hand hole and a reinforcing strip secured to the end pieces above the top edge of the hand hole and opening and extending laterally beyond the ends of the hand 50 hole.

2. An end construction for a carton having a

bottom and side walls, comprising a pair of cardboard end pieces positioned face-to-face in contact with each other and secured at three sides to the bottom and sides of the carton, one of said end pieces having a hand hole spaced from the 5 top edge thereof, the other end piece having an opening in alignment with said hand hole and a reinforcing strip secured to and between the end pieces above the top edge of the hand hole and opening and extending laterally beyond the ends of the hand hole. 10

3. An end construction for a carton having a bottom and side walls, comprising a pair of cardboard end pieces positioned face to face in contact with each other and secured at three sides to the bottom and sides of the carton, said end pieces having aligned openings therein providing a hand hole, the opening in the inner piece being of substantially greater length laterally of the end piece than the aligned opening in the outer piece and the material cut from the opening in the inner piece being bent about the upper edge of the opening into position between the end pieces and above the hand hole. 15

4. An end construction for a carton having a bottom and side walls, comprising a single sheet of material folded double along the upper edge of the end piece and secured at three sides to the bottom and sides of the carton, the outer layer of said end piece having a hand hole therein 20 and the inner layer having an aligned opening of greater width laterally of the end piece than said hand hole, with the material cut from the opening in the inner layer being folded about the upper edge of said opening into the space between 30 the inner and outer layers of the end piece above the hand hole. 25

5. An end construction for a carton having a bottom and side walls comprising a single sheet of material folded double along the upper edge 40 of the end piece to form inner and outer end layers substantially coextensive in area with each other and secured at three sides to the bottom and sides of the carton, the outer layer of said end piece having a hand hole therein and the inner layer having an opening in alignment with 45 said hand hole, and a reinforcing member secured to and between the layers above the top edge of the hand hole and opening, and extending laterally beyond the ends of the hand hole. 50
